COMBINATION CATALYTIC AND THERMAL CRACKING

Joseph Mason Barron, Port Arthur, Tex., assignor
to The Texas Company, New York, N. Y., a
corporation of Delaware

Application July 2, 1943, Serial No. 493,206

7 Claims. (Cl. 196—49)

This invention relates to a combination catalytic and thermal method of cracking hydrocarbons for the production of gasoline or motor fuel.

The invention contemplates a process in which hydrocarbons are subjected to thermal cracking in a reaction zone in which liquid and vapors are in countercurrent contact at cracking temperature and in which the separated vapors from the thermal reaction zone are subjected to catalytic cracking. In accordance with the invention relatively light hydrocarbons undergoing cracking are introduced to the lower portion of a thermal reaction zone and a higher boiling hydrocarbon oil is introduced into an upper portion of the reaction zone to flow countercurrently to the upwardly rising vapors therein and the separated vapors are passed directly to a catalytic cracking step. The refluxing to which the vapors are subjected while undergoing cracking in the countercurrent cracking zone functions to prevent the delivery to the subsequent catalytic cracking zone of certain heavy potential carbon-forming polymers with the result that the vapors from the countercurrent cracking zone may be subjected directly to catalytic cracking without injurious deposition of carbon on the catalyst. It is not necessary to subject the vapors from the reaction zone to any intervening dephlegmation in order that the vapors may be in a suitable condition for catalytic cracking. By carrying on a thermal cracking step in which the vapors undergoing cracking are dephlegmated with the higher boiling stock, the carbon residue of the vapor steam may be kept sufficiently low that the vapors may be contacted directly with the catalyst and subjected to catalytic cracking.

In accordance with the invention relatively low boiling hydrocarbons, such as naphtha and normally gaseous hydrocarbons, are passed through a heating zone and subjected to thermal conversion, while relatively higher boiling condensate stocks, such as kerosene and gas oil, are passed through a second heating zone and subjected to thermal conversion and the heated effluent from these heating zones is distributed between the countercurrent thermal cracking zone and the catalytic cracking zone. Thus, in accordance with the invention, the heated effluent from the heating zones may be combined and a portion of the combined effluent introduced to the lower portion of the countercurrent cracking zone and the other portion combined with the vapor stream issuing from the countercurrent reaction zone for delivery to the catalytic cracking zone. In an alternative method contemplated by the invention

the heated effluent from one of the heating zones is introduced to the lower portion of the countercurrent cracking zone, while heated effluent from the other heating zone is combined with the vapors issuing from the countercurrent cracking zone for delivery to the catalytic cracking zone. In this way the temperature of the vapor stream passing from the countercurrent thermal reaction zone to the catalytic cracking zone is modified and vapors are delivered to the catalytic cracking zone at the exact temperature desired.

The invention will be more clearly understood from the following description and from the accompanying drawing or flow diagram which illustrates diagrammatically a preferred embodiment of the apparatus or system adapted for carrying out my improved combination cracking process.

Crude petroleum, or topped crude, is introduced by a pump 10 to a heating coil 11 disposed in a furnace 12 wherein the oil is heated sufficiently to flash off the fractions desired. The heated oil is passed to a fractionator or a flash tower 13 wherein vapors separate from residue and wherein the vapors are fractionated to obtain a plurality of fractions, such as a higher boiling condensate collected in a tray 14, an intermediate condensate collected in a tray 15, and a lighter vapor fraction which is passed to a condenser coil 16. In case the crude oil contains light gasoline constituents it is preferable to first distill off the light gasoline, as by means of heat exchange with hot products of the system, and to charge the skimmed or topped crude to the heating coil 11 and take off a heavy naphtha fraction as the overhead fraction.

Gas oil is withdrawn from tray 14 and directed by a pump 17 to a heating coil 18 disposed in a furnace 19 wherein the oil is heated to a cracking temperature and subjected to thermal cracking. The heated effluent from the cracking coil 18 passes through a transfer line 20 which extends to the lower portion of a thermal reaction chamber 21. A heavy naphtha fraction is withdrawn from tray 15 and directed by a pump 22 to a heating coil 23 disposed in a furnace 24 wherein the gasoline constituents are subjected to cracking temperatures adequate to effect thermal reforming into constituents of increased anti-knock quality. The products of the reforming pass through a transfer line 25 which is connected to the transfer line 20.

The reaction chamber 21 is vertically disposed and heat-insulated to maintain thermal cracking temperatures therein. The transfer line 20 ex-

tends within the lower portion of the reaction chamber and terminates in an enlarged pipe or section 26 through which the heated products are discharged in an upward direction against a baffle 27. In practice with a three-inch transfer line the element 26 may be composed of a six-inch pipe. The products passing from either or both of the cracking coils 23 and 18 will consist largely of vapors and gases and, upon being discharged through the enlarged pipe 26 against the baffle 27, an efficient diffusion of the vapors and gases is accomplished.

Residue from the flash tower 13 is directed by a pump 28 through a line 29 to a heating coil 30 disposed in a furnace 31 wherein the oil is either subjected to mere preheating or is subjected to temperatures sufficient for cracking or visbreaking. The heated residue passes through a transfer line 32 to the upper portion of the thermal reaction chamber 21. A by-pass line 33 is provided so that any portion or all of the crude residue may be passed directly to the reaction chamber 21. The line 32 extends within the reaction chamber and terminates in a distributor or spray nozzle 34. The spray 34 is arranged to spray the liquid oil in a downward direction through the chamber so as to bring the liquid into intimate contact with the rising vapors. It is desired to have an unobstructed space between the distributor 27 and the spray nozzle 34 free from baffles or other contact elements upon which coke might deposit. Thus the crude residue, either with or without a preceding visbreaking in the heating coil 30, is subjected to thermal cracking in countercurrent with the rising vapors in the reaction chamber.

The separated vapors from the thermal reaction chamber 21 pass through a vapor line 35 to a catalytic cracking zone 36 and hot products are introduced through a line 37 into the vapor stream flowing to the catalytic reaction zone. The line 37 is provided with a branch line 38 communicating with the transfer line 20 prior to the juncture of the latter with the transfer line 25; the line 37 is also provided with a branch line 39 communicating directly with the transfer line 25 and with a branch line 40 communicating with the transfer line 20 beyond the point of juncture with the line 25. These connections provide for the following methods of operation: the delivery of all or a portion of the effluent from the heating coil 18 through line 37 to the catalytic cracking zone 36, the delivery of all or a portion of the effluent from reforming coil 23 through the line 37 to the catalytic cracking zone, and the delivery of any desired portion of the mixed effluent from these heating coils through the line 37 to the catalytic cracking zone, with the delivery in each case of the remaining effluent to the lower portion of the thermal reaction chamber 21. The countercurrent method of cracking in the reaction chamber 21 enables the maintenance of relatively high cracking temperatures therein, such as temperatures in excess of 900° F., without coking and, consequently, facilitates the delivery of a vapor stream from the thermal reaction chamber to the catalytic cracking zone at temperatures approximating those suitable for catalytic cracking. By directing heated products from either or both of the heating coils 23 and 18 into the vapor stream flowing to the catalytic cracking zone the vapor stream is raised to the exact temperature desired for the catalytic cracking. In contact with the catalyst, conversion into lower boil-

ing constituents occurs and reforming reactions, particularly isomerization and hydrogenation of olefins, take place which function to increase the anti-knock quality of the gasoline produced in the thermal cracking operation.

The catalyst consists advantageously of a synthetic silica-alumina type of catalyst. Various acid-treated and metal-substituted clays such as the Super-Filtrols and acid-treated and metal-substituted natural or artificial zeolites, such as the artificial zeolite known as Doucil may be employed. Various metals such as uranium, molybdenum, manganese, lead, zinc, zirconium, nickel and the like, may be substituted in the clays or zeolites. Likewise, the combination of certain acid-treated active clays of the character of Filtrol, together with added proportions of alumina or silica or both may be employed. Alumina alone may be used under certain conditions. The synthetic alumina catalysts can be improved by the addition of other constituents such as zirconium oxide or molybdenum oxide. The catalyst may be provided as a stationary bed through which the vapors pass, or the vapors may pass over a continuously moving mass of granular catalyst, or the catalyst in a finely divided, comminuted or powdered form may be suspended in the vapors being introduced into the reaction chamber, or suspended in a gaseous medium whereby the catalyst is carried along with the vapors through the reaction zone. In the fixed bed method of catalytic cracking a plurality of catalyst chambers may be used so that the catalyst may be regenerated without interrupting the continuity of the complete process, and in the case of the moving catalyst, the catalyst may be removed from the contacting reaction zone to a regenerating zone.

The products of the catalytic cracking are directed through a line 41 to a fractionator 42. The fractionator 42 is formed with a separating or evaporating section 43 into which the catalytically cracked products are discharged and a fractionating section 44 with an intervening condensate tray 45. Reflux condensate collecting in the tray 45 is withdrawn by a pump 46 and directed through a heating coil 47 disposed in a furnace 48 wherein the oil is heated to a cracking temperature and subjected to thermal cracking. The effluent from the cracking coil is discharged into the evaporating section 43 for fractionation together with the effluent from the catalytic cracking operation. Residue is withdrawn through a line 49. Uncondensed vapors pass from the fractionating section 44 to a condenser 50 and the gasoline or naphtha distillate is collected in an accumulator or gas separator 51.

Residue from the thermal cracking chamber 21 is withdrawn through a line 52 to a coking drum 53. The residue is withdrawn rapidly from the reaction chamber so as to prevent the accumulation of liquid residue therein. By reason of the countercurrent method of operation in the reaction chamber, temperatures in excess of 900° F. may be maintained therein without coking and by merely flashing the withdrawn residue in the coking drum, a conversion to a coke residue may be accomplished therein solely by means of the contained heat of the withdrawn residue. In practice a plurality of coking drums are employed so as not to interrupt the continuous operation of the complete process for the purpose of coke removal. The vapors from the coking drum pass to a fractionator 54, being subjected to a primary dephlegmation in a primary

dephlegmating section 55 and to further fractionation in a succeeding fractionating section 56. Primary dephlegmator or polymer fuel oil is withdrawn through a line 57. Reflux condensate from fractionating zone 56 is withdrawn through a line 58. This condensate is normally conducted by a pump 59 through a line 60 and combined with the straight-run gas oil being charged to the heating coil 18. The overhead vapors from the fractionator 54 pass to a condenser 61, thence to a distillate receiver or gas separating drum 62. This distillate may be withdrawn from the system or refluxed in the fractionator 44; preferably, however, it is combined with the condensate being directed to the heating coil 18 by the pump 59.

In a modification of the invention the heated products from the cracking coil 47 may be directed to the lower portion of the countercurrent reaction chamber 21, although generally it is preferable to discharge the heated products to the separating zone 43 or to fractionate the heated products separately.

In an example of the invention straight-run naphtha is passed through a heating coil and subjected to thermal reforming at a temperature of 1050-1100° F. Straight-run gas oil is subjected to thermal cracking by passage through a heating coil with a temperature of 1020° F. in the coil outlet. Topped crude, at a temperature of 760° F., is introduced to the upper part of the thermal countercurrent reaction chamber. The entire product from the reforming coil and a portion of the effluent from the gas oil cracking coil are delivered to the bottom of the countercurrent reaction chamber which is maintained under a pressure of 400 p. s. i. and with a temperature approximating 930° F. in the lower part of the chamber. Residue is withdrawn from the bottom of the chamber and flashed to coke by means of its contained heat. Vapors are withdrawn from the top of the countercurrent cracking chamber at a temperature of 910° F. and the other portion of the effluent from the gas oil cracking coil is combined with the withdrawn vapors to raise the temperature of the vapor stream which is subjected to catalytic cracking at a temperature of 960° F. under a pressure of 75 p. s. i. in contact with a synthetic composite comprising precipitated silica and alumina. The products of the catalytic cracking are fractionated and the catalytic gas oil is subjected to recycling thermal cracking in the heating coil at 980° F. under 600 p. s. i.

In a second example the process is conducted as in the preceding example except that gas oil obtained in fractionating the vapors from the coking operation is added to the straight-run gas oil for passage through the gas oil cracking coil.

In a third example straight-run naphtha is subjected to thermal reforming at a temperature in the outlet of the coil of 1000° F. and introduced to the lower part of the thermal reaction chamber while topped crude, at a temperature of 760° F., is introduced to the upper part of the thermal reaction chamber, which is maintained under a pressure of 400 p. s. i. and with a temperature in the lower part of about 930° F. The residue is withdrawn and flashed to coke by means of its contained heat. Straight-run gas oil is passed through a heating coil and rapidly raised to a temperature of 975° F., with the time of subjecting to the high cracking temperatures being so limited that thermal cracking is reduced to a minimum. The entire product from the

heating coil is combined with the vapors passing from the top of the thermal reaction chamber and the commingled stream is subjected to catalytic cracking in contact with a synthetic silica-alumina catalyst at a temperature of 880° F. In this operation the straight-run gas oil, without substantial thermal cracking, is subjected to catalytic cracking while the thermally reformed naphtha is subjected to a catalytic reforming or finishing operation serving to further increase the octane value and to increase the susceptibility to tetraethyl lead for motor fuel purposes.

The gasoline product obtained in either or both of the receivers 51 and 62 may be subjected to rectification to produce a stabilized gasoline product and, in such case, it is sometimes advantageous to obtain from the rectification a normally gaseous fraction consisting essentially of C₃ and C₄ hydrocarbons, and to combine this fraction with the straight-run naphtha for naphtha reversion in the coil 23 or to combine the fraction for reversion with the gas oil undergoing cracking in the heating coil 18. In lieu of subjecting the normally gaseous fraction to conversion with naphtha or gas oil it may be subjected to a polymerizing action in a separate conversion coil which may discharge into the transfer line 20 for introduction to the thermal reaction chamber.

Although a preferred embodiment of the invention has been described herein, it will be understood that various changes and modifications may be made therein, while securing to a greater or less extent some or all of the benefits of the invention, without departing from the spirit and scope thereof.

I claim:

1. In the combination thermal and catalytic cracking of hydrocarbon oils the process that comprises passing hydrocarbon oil through a heating zone wherein it is heated to a cracking temperature and subjected to thermal cracking, introducing a portion of the resultant heated products into the lower portion of a vertically disposed reaction chamber, introducing a higher boiling hydrocarbon oil to the upper portion of the vertically disposed reaction chamber to flow countercurrently to the upwardly rising vapors therein, maintaining a cracking temperature in said reaction chamber and separating vapors from residue therein, passing the separated vapors to a catalytic cracking zone wherein the vapors are contacted with a catalyst and subjected to catalytic cracking, and combining the other portion of the heated products from said heating zone with the vapors passing to the catalytic cracking zone to control the temperature therein.

2. In the combination thermal and catalytic cracking of hydrocarbon oils the process that comprises introducing heated vapors to the lower portion of a vertically disposed reaction chamber wherein separation of vapors from liquid residue takes place, introducing a residual oil to the upper portion of the vertically disposed reaction chamber to flow countercurrently to the upwardly rising vapors therein, maintaining a cracking temperature in said reaction chamber to effect thermal cracking, passing the separated vapors to a catalytic cracking zone wherein the vapors are contacted with a catalyst and subjected to catalytic cracking, passing a lower boiling hydrocarbon through a heating zone wherein it is subjected to thermal conversion, passing a higher boiling stock through a second heating zone

wherein it is subjected to thermal cracking, utilizing the effluent from one of said heating zones to constitute the said heated products introduced to the lower portion of the vertically disposed reaction chamber, and combining the effluent from the other of said heating zones with said vapors passing to the catalytic cracking zone.

3. In the combination thermal and catalytic cracking of hydrocarbon oils the process that comprises introducing heated vapors to the lower portion of a vertically disposed reaction chamber wherein separation of vapors from liquid residue takes place, introducing a residual oil to the upper portion of the vertically disposed reaction chamber to flow countercurrently to the upwardly rising vapors therein, maintaining a cracking temperature in said reaction chamber to effect thermal cracking, passing the separated vapors to a catalytic cracking zone wherein the vapors are contacted with a catalyst and subjected to catalytic cracking, passing a lower boiling hydrocarbon through a heating zone wherein it is subjected to thermal conversion, passing a higher boiling stock through a second heating zone wherein it is subjected to thermal cracking, combining the effluent from said heating zones, utilizing a portion of the mixture to constitute the said heated products introduced to the lower portion of the vertically disposed reaction chamber and combining the other portion with the vapors passing to the catalytic cracking zone.

4. In the combination thermal and catalytic cracking of hydrocarbon oils the process that comprises distilling a crude petroleum to obtain residue and vapors and fractionating the vapors to obtain a higher boiling fraction and a lower boiling fraction therefrom, passing said lower boiling fraction through a heating zone wherein it is subjected to thermal conversion, introducing the resultant heated products to the lower portion of a vertically disposed reaction chamber wherein separation of vapors from liquid residue takes place, introducing said residue to the upper portion of the vertically disposed reaction chamber to flow countercurrently to the upwardly rising vapors therein, maintaining a cracking temperature in said reaction chamber to effect thermal cracking, passing the separated vapors to a catalytic cracking zone wherein the vapors are contacted with a catalyst and subjected to catalytic cracking, passing the higher boiling fraction obtained in fractionating the crude oil vapors through a heating zone wherein it is subjected to thermal cracking, and combining the resultant heated products with said vapors passing to the catalytic cracking zone.

5. In the combination thermal and catalytic cracking of hydrocarbon oils the process that comprises fractionating crude petroleum to separate naphtha, gas oil and residual fractions, passing the naphtha fraction through a heating zone wherein it is subjected to reforming, introducing the resultant heated products to the lower portion of a vertically disposed reaction chamber wherein separation of vapors from liquid residue takes place, introducing the residual fraction to the

upper portion of the vertically disposed reaction chamber to flow countercurrently to the upwardly rising vapors therein, maintaining a cracking temperature in said reaction chamber to effect thermal cracking, passing the separated vapors to a catalytic cracking zone wherein the vapors are contacted with a catalyst and subjected to catalytic cracking, passing the gas oil fraction through a heating zone wherein it is subjected to thermal cracking, and combining resultant heated products with said vapors passing to the catalytic cracking zone.

6. In the combination thermal and catalytic cracking of hydrocarbon oils the process that comprises introducing heated vapors to the lower portion of a vertically disposed reaction chamber wherein separation of vapors from liquid residue takes place, introducing a residual oil to the upper portion of the vertically disposed reaction chamber to flow countercurrently to the upwardly rising vapors therein, maintaining a cracking temperature in said reaction chamber to effect thermal cracking, passing the separated vapors to a catalytic cracking zone wherein the vapors are contacted with a catalyst and subjected to catalytic cracking, passing a lower boiling hydrocarbon through a heating zone wherein it is subjected to thermal conversion, passing a higher boiling stock through a second heating zone wherein it is subjected to thermal cracking, utilizing the effluent from one of said heating zones to constitute the said heated products introduced to the lower portion of the vertically disposed reaction chamber, combining the effluent from the other of said heating zones with said vapors passing to the catalytic cracking zone, fractionating the resultant products from the catalytic cracking to separate lower boiling products from higher boiling products and subjecting said higher boiling products to cracking conditions of temperature and pressure to effect thermal cracking.

7. In the combination thermal and catalytic cracking of hydrocarbon oils the process that comprises passing naphtha through a heating zone wherein it is heated to a cracking temperature adequate to effect thermal reforming, delivering the resultant heated products to the lower portion of a vertically disposed reaction chamber wherein separation of vapors from liquid residue takes place, introducing a residual oil to the upper portion of the vertically disposed reaction chamber to flow countercurrently to the upwardly rising vapors therein, maintaining a cracking temperature in said reaction chamber to effect thermal cracking, passing the separated vapors to a catalytic cracking zone wherein the vapors are contacted with a catalyst and subjected to catalytic cracking, passing a gas oil stock through a heating zone wherein it is rapidly raised to a cracking temperature, removing the resultant heated products from the heating zone before substantial thermal cracking takes place and combining the heated products with the vapors passing to the catalytic cracking zone.

JOSEPH MASON BARRON.
